Attorney:

UNITED STATES PATENT OFFICE.

ARTHUR W. LYDA, OF NORTH CANTON, OHIO, ASSIGNOR TO THE AMERICAN SAFETY NAVIGATION COMPANY, OF CANTON, OHIO, A CORPORATION OF OHIO.

LIFEBOAT AND DAVIT.

Application filed July 12, 1922. Serial No. 574,420.

To all whom it may concern:

Be it known that I, ARTHUR W. LYDA, a citizen of the United States, residing at North Canton, in the county of Stark and 5 State of Ohio, have invented a new and useful Lifeboat and Davit, of which the following is a specification.

This invention relates to life boats and davits for carrying and raising and lowering the same.

The objects of the invention are to provide davits pivoted at their lower ends to the deck and arranged to swing outward upon their pivots to lower the life boat, 15 saddles being carried by the davits for supporting the life boats in the inoperative position, the life boat and davits being held in this position by means of a windlass which controls the cables upon which the 20 life boats are raised and lowered; means being provided for automatically releasing the life boat from the cables as the boat reaches the surface of the water; means being also provided for automatically releasing 25 the life boat from the davits in the event the water reaches the level of the life boat before the same has been lowered; means also being provided for controlling the lowering of the life boat from the life 30 boat itself as the same is being lowered and for applying a brake to the driving mechanism which controls the lowering of the boat to stop the boat at any level.

The above and other objects may be attained by constructing the mechanism as 35 illustrated in the accompanying drawings, in which—

Figure 1 is a perspective view of a life boat provided with davits and raising and lowering mechanism embodying the invention, showing the same from the deck side 40 of the mechanism;

Fig. 2, a perspective view of the mechanism showing the life boat in the partly lowered position;

Fig. 3, a perspective view of the mechanism from one end of the boat;

Fig. 4, a transverse sectional view through the boat showing the saddle upon 45 the davit for supporting the boat in raised position, taken upon the line 4—4, Fig. 1;

Fig. 5, a plan view of the driving and controlling mechanism;

Fig. 6, an elevation of the automatic release for the controlling mechanism;

Fig. 7, a longitudinal sectional view through the automatically releasable hook;

Fig. 8, a detail view of the finger upon the davit for holding the trunnion of the boat in the raised position upon the davit; 60

Fig. 9, a section on the line 9—9, Fig. 5; and

Fig. 10, a section on the line 10—10, Fig. 5.

Similar numerals of reference indicate 65 corresponding parts throughout the several figures of the drawings.

A portion of the side of a ship is shown at 1, and a fragmentary portion of the deck at 2. A spaced pair of standards 3 are 70 mounted upon the deck at the proper distance apart to accommodate the life boat indicated generally at 4. Each of the standards 3 comprises a base portion 5 secured to the deck near the side of the ship, 75 as best shown in Fig. 3, a pair of spaced uprights 6 being fixed thereon.

A rotatable shaft 7 is journaled through the lower portion of each standard and the davits 8 are journaled upon said shaft at 80 their lower ends as by the forked bearing portion 9, each davit being arranged to be received between the uprights 6 when in the raised position.

A drum or spool 10 is fixed upon the 85 shaft between each pair of uprights 6, a cable 11 being fixed at one end to each drum, the free end thereof extending upward over a pulley 12 carried at the upper end of the standard 3 and over a pulley 13 90 upon the free end of the davit 8, having connected to its free extremity the automatically releasable hook 14 illustrated in detail in Fig. 7.

This hook comprises a pair of spaced 95 plates 15 connected at their upper ends as by the boss 16 which is internally threaded as at 17 to receive the threaded shank 18 of the eye 19 by means of which the hook is connected to the cable. The curved hook 100 member 20 is pivoted as at 21 to the lower end portions of the plates 15 between the same and provided with the squared upper extremity 22 normally engaged by the shoulder 23 upon the releasing lever 24, 105 which is provided with the depending weighted arm 25.

The plunger 26 is slidably mounted 110 through the bearing members 27 connected to the plates 15 and provided with the

headed shank 28 extending through the slot 29 in the lever 24. The lower end of the plunger 26 is provided with a foot 30 which normally projects beneath the link or eye 31 fixed upon the trunnion 32 of the boat.

It will thus be seen that when the weight of the boat is suspended upon the hook member 20, the link 31 engaging the foot 30 will hold the plunger 26 and with it the lever 24 down, holding the shoulder 23 of the lever in engagement with the squared extremity 22 of the hook 20.

As soon as the downward pull upon the hook member 20 is released, it will be seen that the weight 25 will swing inward, raising the lever 24 and allowing the hook member 20 to drop, releasing the eye or link 31 therefrom. It is pointed out that the plates 15 extend outward beyond the normal position of the weight 25, thus preventing accidental operation of the hook to release the same.

The upper end portion of each of the davits 8 is provided with a curved slotted finger 33, located just beneath the pulley 13, a pair of curved fingers 34 being located beneath and spaced from the finger 33. A ball 35 is fixed upon the cable at the proper point above the releasable hook and is arranged to be normally seated between the finger 33 and the fingers 34 when the boat is in the raised position, as best shown in Fig. 3, the cable extending through the slot in the finger 33 and between the fingers 34.

A rest plate 36 is fixed intermediate the extremities of each davit to receive the adjacent trunnion 32 of the boat when in the raised position, the rear end portion of this rest plate being received in the shouldered portion 37 of the head 38 provided at the upper end of each standard 3.

A holding finger 39 is pivoted as at 40 to the outer end portion of each rest plate 36, a plunger 41 being pivoted as at 42 to each finger beneath the pivotal point thereof and extending through a groove or channel 43 in the rest plate 36, the rear end portion thereof being arranged to engage the shoulder 37 in the head of the standard 3 when the boat is raised as shown in Fig. 3, the plunger being thus pushed forward, raising the finger 39 as shown in said figure.

A pair of curved or angular arms 44 are fixed to the shaft 7 and extend outward, a rod 45 being rigidly connected to said arms and having mounted thereon the saddles 46 which may be adjusted vertically as desired as by a turnbuckle 47. These saddles as shown in Figs. 1 and 4, support the boat when in the raised position.

A clutch member 48 is slidably mounted upon the shaft 7 and arranged to be moved into engagement with the clutch member 49 which is rotatably mounted upon the shaft and journaled in the bearing 50, a

worm wheel 51 being fixedly connected to the clutch member 49 and engaging the worm 52 mounted upon a shaft 53, which carries the gear 54 meshing with the pinion 55 upon the shaft of the motor 56.

The clutch member 48 is arranged to be slidably moved upon the shaft 7 as by means of the lever 57 which is pivoted as at 58 upon a stationary portion of the device and engaged by the angular operating handle 59. The speed of the rotation of the shaft 7 may be regulated by means of the gearing 60 and the pallet or fan 61.

A brake drum 62 is provided upon the shaft 7, a brake band 63 being located around the same, one end being connected to the lever 64 to which is connected the cable 65, extending through an aperture or slot in the housing 66, the free end of the cable being located in the boat. If desired, a windlass provided with any suitable form of brake mechanism, may be provided in the boat to receive the cable 65. By this construction, it will be seen that the brake may be applied to the shaft 7 by a person within the boat, thus making it possible to control the lowering of the boat from the boat itself.

A lug 67 is fixed upon the inner side of the boat and arranged to be received in the bifurcated portion 68 of the bracket 69, a locking pin 70 being slidably mounted through said bifurcated portion and arranged to engage the lug 67 as best shown in Fig. 5, when the boat is in the raised position, to prevent the same from being removed.

A finger 71 is provided upon the locking pin 70 and extends through the slot 72 in the bracket 69. A float 73 is mounted upon the vertical rod 74 fixed upon the deck and is provided with the arm 75 having the hook extremity 76 which normally engages the pin 71, preventing accidental withdrawal of the locking pin. The handle 59, when in the normal position, is engaged with the finger 71 as shown in Figs. 5 and 6.

The operation of the device may be described as follows; the several parts being in the normal position, as shown in Figs. 1, 3, 4, 5, 6 and 7, when it is desired to lower the life boat, the boat is manned by the crew in the usual manner and the passengers are loaded therein, after which the handle 59 is pushed to the left, that is, toward the finger 71, releasing the finger from the hook 76 and moving the same into the notch 77 in the slot 72, withdrawing the locking pin 70 from engagement with the lug 67 of the boat, releasing the boat from engagement with the bracket 69.

This movement of the handle 59 will also throw the lever 57 to disengage the clutch member 48 from the clutch member 49 and the weight of the boat hanging upon the

- 5 davits will swing the same immediately into the position shown in Fig. 2, the cables 11 unwinding freely from the drums 10. The cable 65 will be operated by one of the crew in the boat 5 to regulate the speed of the descent of the boat, the brake being applied to the shaft 7 whenever it is desired to slow up the speed of the boat or to stop the same entirely in its descent.
- 10 5 It will be seen that the chains 78 upon the heads 38 of the standards limit the outward movement of the davits 8, as best shown in Fig. 2. It will also be understood that as the davits swing outward into this position, 15 the weight of the boat being entirely suspended upon the rests 36 of the davits by means of the trunnions 32, will automatically throw the holding fingers outward into the position shown in Fig. 2, releasing the 20 boat from engagement with these rests and fingers.

As the boat reaches the surface of the water, the pull upon the cables 11 will be slackened, releasing the pull upon the releasable hook, allowing the link or eye 31 to rise sufficiently with relation to the hook member 20 to permit the weight 25 to swing inward, releasing the lever 24 from engagement with the hook member, allowing the 30 same to drop upon its pivotal point 21 and permitting the boat to swing clear of the hook when it will be operated by the crew in the usual manner.

In raising the boat, after the same has been lowered, the davits and cables will be located in the lowered position and the boat brought into place beneath the same and attached to the hooks upon the cables. The handle 59 will then be thrown into the position shown in Figs. 1, 5 and 6, throwing the clutch member 48 into engagement with the clutch 49 and the motor 56 will be started, winding the cables 11 upon the reels 10 and raising the boat until the balls 35 engage 45 the fingers 33 and 34 upon the upper ends of the davits, when the davits will be pulled by the cables into the initial position, best shown in Figs. 1 and 3, seating the boat upon the saddles 46 and seating the trunnions 32 upon the rest members 36, the fingers 39 being automatically raised into the 50 position shown in Fig. 3 into engagement with said trunnions as above described.

The finger 71 will then be operated by 55 hand to withdraw the locking pin 70, permitting the lug 67 upon the boat to be entered into the bifurcated portion 68 of the bracket 69, after which the locking pin will be pushed back to the position shown in Fig. 5, the finger 71 engaging the hook 76, holding the locking pin in the locked position.

In the event the ship is sinking rapidly and prevents any of the life boats from 65 being manned, these particular life boats

will be automatically released from the davits and allowed to float away from the ship as the same sinks. As the water reaches the float 73, the same will be raised with the water, sliding upward upon the 70 rod 74, raising the arm 75 carried thereon, the inclined cam portion 81 of said arm forcing the finger 71 outward in the slot 72, withdrawing the locking pin 70 from engagement with the lug 67 upon the boat and the releasable hooks which connect the boat to the cables will be automatically opened as above described, as the water level raises the boat from the rests 36 upon the davits, thus allowing the boat to float free of the 80 davits.

Persons who have been thrown into the water by the sinking of the vessel, may thus swim to any of the empty life boats which are thus automatically freed from the ship, 85 this in itself providing a great saving of life.

The importance of the automatic control comprising the gearing 60 and fan 61 should not be overlooked, as practical experience 90 has shown that without such a controlling mechanism, the boat would drop suddenly the moment it was released, making it impossible to lower and launch the same without the greatest danger to the occupants. 95 This automatic regulator controls the lowering of the boat, allowing the same to move slowly downward to the surface of the water, while the brake upon the shaft operated from within the life boat itself, permits perfect control of the life boat by the occupants thereof, allowing the same to be stopped at any height or lowered at any desired speed by regulating the tension upon the brake.

100 I claim:—

1. A life boat and davits for a ship including standards mounted upon the ship's deck, a shaft journaled at its ends in the lower portions of said standards, a davit loosely mounted upon each end portion of the shaft, a reel fixed upon each end portion of the shaft, a pulley upon the upper end of each standard, a pulley upon the upper end of each davit, a cable upon each reel extending over the pulleys of the adjacent standard and davit, a life boat suspended upon said cables, means for normally holding the shaft against rotation to retain the boat in the raised position and means for releasing the 110 shaft to permit the cables to unwind from the reels and the davits to swing outward to lower the boat.

2. A life boat and davits for a ship including standards mounted upon the ship's 125 deck, a shaft journaled at its ends in the lower portions of said standards, a davit loosely mounted upon each end portion of the shaft, a reel fixed upon each end portion of the shaft, a pulley upon the upper end of each 130

standard, a pulley upon the upper end of each davit, a cable upon each reel extending over the pulleys of the adjacent standard and davit, a life boat suspended upon said 5 cables, means for normally holding the shaft against rotation to retain the boat in the raised position and means for releasing the shaft to permit the cables to unwind from the reels and the davits to swing outward 10 to lower the boat, and means for automatically releasing the life boat from the cables as the life boat reaches the surface of the water.

3. A life boat and davits for a ship including standards mounted upon the ship's 15 deck, a shaft journaled at its ends in the lower portions of said standards, a davit loosely mounted upon each end portion of the shaft, a reel fixed upon each end portion 20 of the shaft, a pulley upon the upper end of each standard, a pulley upon the upper end of each davit, a cable upon each reel extending over the pulleys of the adjacent standard and davit, a life boat suspended 25 upon said cables, means for normally holding the shaft against rotation to retain the boat in the raised position and means for releasing the shaft to permit the cables to unwind from the reels and the davits to 30 swing outward to lower the boat, and automatically releasable hooks connecting the cables to the life boat and arranged to automatically release the life boat as the same reaches the surface of the water.

4. A life boat and davits for a ship including standards mounted upon the ship's 35 deck, davits pivotally mounted at their lower ends in the standards, a rest upon each davit, reels in the standards, a pulley upon the upper end of each standard, a pulley 40 upon the upper end of each davit, a cable upon each reel extending over the adjacent pulleys, a life boat suspended upon said cables, trunnions upon the life boat arranged to be seated upon said rests and pivoted 45 holding fingers upon the rests arranged to automatically engage the trunnions when the boat and davits are in the raised position.

5. A life boat and davits for a ship including standards mounted upon the ship's 50 deck, a davit pivoted at its lower end in each standard, a pulley upon the upper end of each standard, a pulley upon the upper end of each davit, reels upon the standards, 55 a cable upon each reel extending over the adjacent pulleys, a life boat suspended upon the cables, a locking lug upon the inner side of the life boat, and a slidable locking pin upon the ship normally engaging said 60 lug, a motor for rotating said reels, a clutch between the motor and reels and an operating lever for simultaneously operating the clutch and withdrawing the slidable locking pin.

In testimony that I claim the above, I have hereunto subscribed my name.

ARTHUR W. LYDA.
